G. W. DANA, OF RACINE, WISCONSIN.

Letters Patent No. 86,005, dated January 19, 1869.

IMPROVEMENT IN PERMUTATION-LOCKS.

The Schedule referred to in these Letters Patent and making part of the same.

To all whom it may concern:

Be it known that I, G. W. DANA, of Racine, in the county of Racine, and State of Wisconsin, have invented a new and improved Burglar-Proof Lock; and I do hereby declare that the following is a full, clear, and exact description thereof, which will enable those skilled in the art to make and use the same, reference being had to the accompanying drawings, forming part of this specification.

This invention relates to a new and burglar-proof lock, and is an improvement on a lock for which Letters Patent were granted to me, bearing date December 27, 1859.

The present invention consists in certain appliances, hereinafter fully shown and described, whereby the lock is rendered more secure or invulnerable against picking than heretofore, and also less susceptible of injury in an effort to pick or to open it by force.

In the accompanying sheet of drawings—

Figure 1, Sheet No. 1, is a section of my invention, taken in the line *x x*, fig. 2.

Figure 2, a section of the same, taken in the line *y y*, fig. 1.

Figure 3, a view of the rear side of the lock-case.

Figure 4, a detached side view of one of the spindle-caps pertaining to the same.

Figure 5, a face or end view of fig. 4.

Figure 6, Sheet No. 2, a face view of the socket-plate of the lock.

Figure 7, an inner side view of the front plate of the lock-case.

Figure 8, an outer side view of the front plate of the lock.

Figure 9, a detached view of the key for turning the spindles of the lock.

Similar letters of reference indicate corresponding parts.

A represents the case of the lock, which is of rectangular form, and has fitted within it two slide-bolts, B C, which are operated respectively by wheels D E, the latter being provided, at their peripheries, with semicircular recesses, *a*, to receive corresponding-shaped teeth, *b*, on the wheels D E.

The bolts are moved, and the lock consequently locked and unlocked, by turning these wheels, as will be fully understood by referring to fig. 1.

F represents a series of spindles, which pass transversely through the lock-case A, said spindles being placed in such a position as to form a portion of a circle, and at distances apart corresponding to the distances between the recesses *a* of the wheel D, one-half of the diameter of the spindles extending within the periphery of the wheel D.

These spindles are notched out, as shown at *b*, so that when said notches are all adjusted to face the wheel D, the latter may be turned and the bolt B moved, but when the solid or uncut opposite sides of

the spindles are within the recesses *a* of wheel D, the latter cannot be turned, and consequently the lock not unlocked.

The bolt C is provided with a substantially-similar arrangement, semicircular recesses being made in one edge of said bolt, and a series of notched spindles, G, arranged in line with the recesses.

This arrangement of spindles, and mode of operating the bolts, are precisely the same as shown in my previously-patented lock, and therefore do not require a more extended description.

On the arbor H of the wheel D there is placed, loosely, a wheel, I, similar to wheel D, it being provided with the same semicircular notches, *c*.

The wheel I is connected, by two pins *d d*, with an arm, J, which projects from a hub, K, on an arbor, L, the latter passing through the lock-case.

This hub K also has another arm, M, projecting from it, which is connected, by two pins *e e*, with a slide-bar, N, the latter, when the lock is in a locked state, having its ends *f f* behind the bolts B C, to prevent the latter being thrown back, as will be fully understood by referring to fig. 1.

On the bolt C there is a sliding plate, O, having semicircular recesses, *g*, in its edge which is opposite the spindles G, and this plate is connected, by two pins *e e*, with an arm, M', which also extends from the hub K of arbor L.

In order to unlock the lock, two things are necessary to be done: first, to move the slide-bar N so that its ends *f f* will be out of line with the bolts B C; and second, to turn the wheels D E, in order to slide or shove the bolts back; and in order to effect these results, the spindles F G require to be turned so that the notches *b* of the spindle F will face the wheels D I, and the notches of the spindles G made to face the bolt C and sliding plate O.

This being accomplished, the arbor L is allowed to turn, and the arm M to move the slide-bar N.

By this arrangement the position of the notches in the spindles cannot be ascertained by exerting a pressure on the bolts, as the latter, when the lock is locked, are rendered immovable by the slide-bar N, and the wheels D E cannot be turned so as to press against the spindles.

As a further safeguard, I employ the following means:

On the rear end of the arbor H of the wheel D, and at the outer side of the back plate of the lock-case, a wheel, Q, is placed loosely.

This wheel is constructed with semicircular recesses, *i*, in its periphery, like the wheels D E, as shown clearly in fig. 3, and the rear ends of the spindles F are halved out, so that their flat sides, when the lock is in a locked state, will be directly opposite the spaces between the recesses *i*, the wheel Q being retained in this position by a spiral spring, R, which is attached to it.

S is a dog, one end of which is connected, by two

pins *j*, to the wheel *Q*, and the opposite end, when the wheel *Q* is turned so as to bring its recesses *i* in line with the spindles *F*, engages with a ratchet, *T*, on the arbor *L*.

U is a lever attached to the outer side of the back plate of the lock-case, and extending, at one end, over the wheel *Q*, and near to a pin, *k*.

The opposite end of the lever *U* bears against a cam, *l*, which is on the rear end of a spindle, *G*, designated by *G'*.

The wheel *Q* prevents the spindles *F* being turned when the spaces between its recesses *i* are opposite the flat surfaces of the spindles, and consequently the position of the notches *b* in the spindles cannot be ascertained.

In order to admit of the spindles *F* being turned, in order to unlock the lock legitimately, the spindle *G'* is turned so that the cam *l* will actuate the lever *U*, and the latter turn the wheel *Q*, so as to bring the recesses *i* in line with the spindles *F*, and in thus turning the wheel *Q*, the dog *S* is thrown in connection with the ratchet *T*, and the arbor *L* and slide-bar *N* cannot then be turned; hence, when the spindles *F* can be turned, the slide-bar *N* cannot be moved, nor the bolts *B* *C* acted upon or pressed back, and the lock is therefore rendered unpickable, or burglar-proof.

In order to prevent the spindles *F* *G* being injured by force, I have each provided with a cap, *V*, the inner ends of which are in against metallic boxes, *W*, in a socket-plate, *X*, (see fig. 2,) the outer ends of the caps being notched, to receive the bits *m* of the key *Y*.

These caps are fitted loosely on the spindles, but are connected therewith by plates *Z*, which are fitted on squares on the spindles, and are provided with projections or ribs, *n*, to fit into grooves, *o*, in the inner ends of the caps.

A' is a circular plate, fitted loosely on the arbor *H* of the wheel *D*, at the outer side of the front plate of the lock.

This plate has a circular hole, *p*, made in it, and said plate covers the outer ends of the caps *V*.

By turning this plate the caps *V* can be consecutively exposed, and the spindles properly adjusted in unlocking and locking the lock.

The plate *A'* conceals the ends of the caps, preventing them being seen when the lock is in an unlocked state.

This circular plate *A'* is fastened, when the lock is unlocked, as follows:

On the arbor *H* there is a hub or boss, *B'*, having a spiral groove, *r*, made in it, to operate a lever, *C'*, and throw a pin-projection, at the outer end of said lever, into the rear side of plate *A'*.

In throwing out the bolt *B*, the plate *A'* is unlocked, and it is locked by lever *C'*, as said bolt is thrown back.

I would remark that the caps *V* are lettered, as also the key, and the hole *p* in plate *A'*; and also the hole in the front plate of the lock, in which the caps *V* of the spindles *G* are fitted, are numbered, to serve as guides in adjusting the spindles.

The front plate of the lock, around plate *A'*, is also numbered, to serve as a guide in adjusting or turning said plate.

I claim as new, and desire to secure by Letters Patent—

1. The plate *O*, fitted on the bolt *C*; and provided with the semicircular recesses, and connected with the slide-bar *N*, as shown and described, when said parts are used in connection or combination with the wheels *I* and *D*, bolts *B* *C*, and the notched spindles *F* *G*, all arranged to operate in the manner substantially as and for the purpose set forth.

2. The wheel *Q*, on the arbor *H* of wheel *D*, provided with the semicircular recesses *i*, and having the spring *R* connected with it, in combination with the dog *S*, ratchet *T* on arbor *L*, lever *U*, and the cam *l* on the spindle *G'*, all arranged to operate in connection with the spindles *F* and slide-bar *N*, substantially as set forth.

3. The circular plate *A'*, provided with the opening, *p*, in combination with the grooved hub *B* on the arbor *H*, and lever *C'*, to serve as a lock for said plate, all arranged substantially as shown and described.

G. W. DANA.
